UNITED STATES PATENT OFFICE

2,522,173

LEG AND FOOT REST

Lionel Herbert, Charlotte, N. C.

Application September 4, 1946, Serial No. 694,784

14 Claims. (Cl. 128—83)

1 This invention relates to improvements in leg and foot rests, particularly of the character adapted to support one or both legs to form a rest therefor, when a person is in a sitting or lying position. It is an improvement on the character of leg and foot rest set forth in my prior patent, No. 2,375,225, granted May 8, 1945.

It is often desirable or necessary to support and rest one or both legs of a person who may be lying in a bed or sitting in a chair with the leg or legs in an elevated position, not only for comfort but also to improve the healing effect of treatments applied thereto, especially when traction is imparted to the limbs. Heretofore, such leg rests and supports as have been used, especially in hospitals, have involved complicated supporting structures either permanently attached to the bed or formed as frames that extend over and about the bed, which were so bulky and cumbersome as to be highly objectionable. They have been of permanent erected structures that were not capable of removal or of movement from bed to bed as is often desired.

The object of this invention is to improve the construction of such leg and foot rests, by simplifying them, rendering the device less expensive to manufacture and at the same time making it possible to attach the rest removably to a bed or chair, so that it may be detached therefrom when not required for movement to other beds or for storage in an accessible place.

A further object of the invention is to improve the construction of such leg rests to adapt them not only for supporting the legs and feet in different positions but also for improving the comfort resulting from such use as well as to apply traction to the feet when supported on such a rest. Thus improved facilities are provided according to this invention for treating leg and foot injuries, in certain cases, without the necessity for the cumbersome and permanent frames heretofore required in commercial practice.

The leg and foot rest has provision for anchoring it to the support for a patient, such as a bed or a chair, and may be used for either leg or both at once and at the same time it is capable of being adjusted to different positions by the action of the patient himself or attendant, inasmuch as such attachments are easily accessible to him and are capable of ready variation as desired. Thus it is possible for the patient to obtain the maximum comfort from such a rest either when applied to one or both legs by adjusting the angle and length of the leg support, the bending of the knee when desired, the position of the foot rest,

or the like, and the latter is capable also of applying traction to the foot and leg when required.

The invention may be embodied in a structure that is capable of attachment to one or both sides of a bed and to form a stationary frame that will support the leg or legs of the patient thereon either flat on the bed or in an elevated position with respect thereto. It can be used for one or both legs as desired, and if only one leg is to be supported, the trough for the other leg is capable of removal, leaving the patient free to change his position to any extent desired while yet supporting the one leg in the trough either in an elevated position or flat on the bed, according to the character of treatment being applied. The frame that supports the trough forms a secure attachment thereof to the bed that makes it capable of holding the supporting trough in different positions with the portions thereof either aligned or bent at an angle to accommodate the bent knee joint, for improved effect and comfort.

The invention is illustrated in different embodiments in the accompanying drawings, in which:

Fig. 1 is a side elevation of the leg and foot rest shown in position on a bed;

Fig. 2 is an end elevation thereof with the bed rails in section;

Fig. 3 is a top plan view thereof;

Fig. 4 is a bottom plan view of a portion of one of the leg troughs;

Fig. 5 is a transverse section therethrough on the line 5—5 of Fig. 4;

Fig. 6 is an end elevation of one of the troughs showing the foot support and traction device;

Fig. 7 is a detail elevation of the opposite end of the trough with the supporting frame in section, taken on the line 7—7 of Fig. 3;

Fig. 8 is a cross section through one of the troughs at the joint therein;

Fig. 9 is a longitudinal section therethrough;

Fig. 10 is a side elevation of one of the frame clamps;

Fig. 11 is a vertical section therethrough;

Fig. 12 is a top plan view showing a modified form of leg rest structure; and

Fig. 13 is a side elevation showing a modified form of supporting frame.

The invention is adapted to support the leg or legs of a patient either when lying in bed or sitting in a chair, with the legs stretched outward or inclined or bent at the knees when desired, and it is capable of supporting one leg only as desired.

It is shown as applied to a bed generally design-

nated at B in Fig. 1, and as clamped to side rails 1 of the bed, by detachable fastenings capable of being separated therefrom when not required.

Separate leg supports are provided for the respective legs when both are to be supported therein, formed in the shape of troughs. Each of these troughs is mounted on a supporting frame at each opposite side of the bed as designated generally at 2, as shown generally in Figs. 1, 2 and 3.

Each of the frames 2 is shown as bifurcated with depending arms 3, shown as formed of steel tubes and joined together at the top by a rigid connection 4 that extends therebetween. A guide tube 5 is secured rigidly to the connection 4 to receive therein a supporting standard 6. This standard 6 is slidable vertically through the tube 5 and is adapted to be secured in a set position with respect thereto as by means of a fastening bolt 7, capable of manual adjustment and tightening on the side of the standard.

The bifurcated arms 3 are adapted to be secured rigidly to the bed rail 1, by clamps which are shown more in detail in Figs. 10 and 11. Each of the clamps includes a guide 8, slidably receiving the arm 3 and adapted to be secured rigidly thereon by a screw 9, capable of manual adjustment to lock the arm 3 securely in rigid relationship to the clamp. The clamp is formed by a clamping plate 10 and a clamping screw 11 that embraces opposite sides of the bed rail 1, to fasten the rail therebetween and secure the clamp thereon. A manually adjustable pin 12 is attached to the clamping screw 11 to facilitate turning thereof when it is desired to lock the clamp on the bed rail.

The standard 6 of each supporting frame is turned inward to form a journal rod designated 13 adapted to extend transversely of the bed and to be in axial alignment with the corresponding rod of the other frame when both of these are used at one time. Extending parallel with the journal rod 13 is a rod 14 which is turned downward at its outer end and telescoped into one of the tubular arms 3 by means of which the rod 14 is adapted to be secured in an adjusted position by means of an adjusting screw 15 threaded through a bushing in one side of the support 3. The rods 13 and 14 are connected together by a link 16 as shown in Figs. 1 and 3, and thereby form an adjustable portion of the supporting frame that may be adjusted vertically relative to the lower portion of the frame that is attached to the bed rail.

Sleeved over the journal rod 13 is a tubular support 17 adapted for mounting of a leg trough thereon. This mounting is by means of bracket 18 permanently fixed at one end to the journal support 17 and extending laterally therefrom. At its outer end, the bracket 18 has an offset portion 19 provided with an arcuate slot 20 therein.

The leg supporting trough is shown as formed in three sections 21, 22 and 23. The section 21 has a stiffener bracket 24 secured as by rivets to the under side thereof, as shown in Figs. 4 and 7, which stiffener bracket extends lengthwise over the bracket 18. The brackets 18 and 24 are pivotally connected together at 25 (Fig. 3), capable of supporting the leg trough 21-23 on the journal sleeve 17, not only for vertical swinging movement relative thereto, but also for lateral swinging movement. For limiting the lateral swinging movement, the bracket 24 is provided with a guide pin 26 that extends in the slot 20 in the arm 19, as will be evident from Fig. 3.

Each of the sections 21-23 of the leg supporting trough is formed preferably of a light rigid

material, such as aluminum or an aluminum alloy, having the necessary rigidity for supporting the leg and yet with the minimum weight capable of adjustment to different positions. It is preferred that the opposite edges thereof be turned over or rolled as indicated at 27 to avoid sharp edges thereon. At its inner corner, the section 21 preferably is cut away or rounded as indicated at 28 to provide for maximum comfort.

The rolled edges 27 also facilitate the telescoping of the sections 22 and 23, as will be evident from Figs. 1 and 3 and form a secure support for the section 23 on the section 22, while yet permitting longitudinal adjustment of the section 23 relative to the section 22 to accommodate legs of different lengths. This may be merely a sliding adjustment, inasmuch as the friction therebetween will be sufficient to hold these parts in their adjusted positions.

The sections 21 and 22 are shown as in longitudinal alignment but preferably are hinged together at 29. This permits the sections 22-23 to be dropped down at an angle relative to the section 21 to accommodate the bending of the knee when desired. The angular disposition of the sections 21 and 22 may be locked in proper relation to each other by a thumb screw 30 which extends through an arcuate slotted clamp 31 on each side of the trough and shown as permanently secured to the section 22. Thus the sections 21 and 22 may be tilted to acute angles relative to each other or in direct longitudinal alignment, as shown in Fig. 1, and secured by the thumb screws 30 in either adjusted position. These thumb screws are within convenient reach of the patient and, therefore, capable of manual adjustment thereby.

Each trough is also capable of being raised and lowered to different angular positions with respect to the bed by turning the journal sleeve 17 upon the journal rod 13 which will swing the bracket 18 and thereby the trough to different angular positions with respect to the bed. This adjustment is accomplished by an upright arm 32 permanently fixed to the sleeve 17 and extending in an upright direction within a convenient reach of the patient, so the patient may make the adjustment when desired. Thus by pulling back on the arm 32, the patient will rotate the journal sleeve 17 on the rod 13 to swing the trough to an upright position which may be adjusted as desired for maximum comfort. The arm 32 may be locked in its adjusted position by a locking catch 33 that engages a toothed segment 34 fixed to the journal rod 13. The catch 33 preferably is spring-pressed and is manipulated by a handle 35 of well-known construction.

Where supports are mounted on the bed for both legs, as shown in Fig. 2, these may be connected together by a yoke 36. The yoke 36 extends transversely over both of the troughs as shown in Figs. 2 and 3, and has down-turned opposite ends telescopically engaging the upper ends of the arms 32 and detachably connected therewith. One or more pins 37 (Fig. 3) may be inserted through the connection, if desired, to insure a rigid connection therebetween, which pins may be withdrawn for separation of the yoke 36 when it is desired to use only one of the leg supports.

At its outer end, each leg trough is provided with a foot support 38 mounted on a transverse rod 39 by a bracket 40. The foot support 38 may be secured in different angular positions with respect to the rod 39, if desired, by a locking screw

40 that extends through the bracket 40 and engages the rod 39.

The rod 39 is shown as mounted at its opposite ends in opposite sides of a yoke 42 which is used for the purpose of applying traction to the foot and leg when desired, although any suitable mounting for the foot support may be provided when such traction is not required. In this form,

the yoke 42 is journaled on rods 43 slidably mounted in blocks 44 at opposite sides of the trough section 23 and capable of being locked in set positions by set screws 45 which are threaded through the blocks 44 into frictional engagement with the rods 43. Each of the blocks 44 has a downwardly inclined arm 46 connected through a link 47 with the lower end of the yoke 42, thereby forming a pivotal connection between the lower end of the yoke and the blocks 44.

By adjusting the rods 43 inward or outward relative to the trough section 23, the foot support 38 likewise is adjusted in a longitudinal direction relative to the trough. When the foot support is secured by bandages or any other secure manner to the foot of the patient, such an adjustment will apply traction to the foot and leg as desired.

The use and operation of the leg and foot rest will be evident from the foregoing description, as well as the fact that it may be applied readily for either or both legs and to be used as desired on a bed, chair or other support on which a patient may be disposed. When the standards 2 are secured to the bed, it will be evident that the leg rests or troughs may be mounted in the proper adjusted positions with respect thereto not only because of the sliding adjustment of the parts 6 and 14 with respect to the arms 3 but also by the separate adjustment of the arms relative to the clamps 10-11. Thus it is capable of being adapted to many different applications and conditions of use as may be found desirable. The leg and foot rest is also adapted to be detached from the support when desired or when not required, for use on other beds without it being necessary to erect such a support as a permanent fixture on a particular bed.

When in use, it will be evident that the patient may make the necessary adjustment himself for maximum comfort either by swinging the arm 32 or by adjusting the position of the trough to whatever he may find most comfortable. The parts then may be secured by the patient in their relative positions.

A modification of the supporting standard is shown in Fig. 13, in which the standard is designated generally at 51, and is adapted to be secured by clamps 52 to the bed rail. An upright support 53 extends upwardly from the standard and is vertically adjustable relative thereto, corresponding with the parts 6, 13, described above. A lateral bracket 54 is carried by the support 53 to replace the rod 14 described above, thus allowing the entire leg and foot rest to swivel off the bed rail. When the bracket 54 is used, the nurse or attendant may swing the rest away from the bed, out of the way, when not in use, or when one rest only is used, or allowing the bed to be made. Otherwise this form of support is used substantially like that described above.

A further modification is shown in Fig. 12 adapted for two leg rests both of which are supported on a yoke 61 that extends transversely over the bed and downwardly at opposite sides thereof. The yoke 61 may be secured to the bed rails by clamps 62.

The troughs are designated generally at 63

and are pivotally connected at 64 with brackets 65 permanently secured as by welding a journal sleeve 66 that is journaled on the rod 61 capable of swinging movement relative thereto. A yoke 67 is fixed to the journal sleeve 66 and extends transversely over the troughs 63 for adjusting the troughs to different angular positions merely by unpulling back on the rod 67.

The troughs may be held in their adjusted position by a yoke 68 that extends transversely between the troughs 63 and downwardly therefrom to pivotal connections at the outer ends of arms 69 that extend laterally from the yoke 67. The yoke 68 may be turned downward flat on the bed to lower the troughs to prone positions or turned upward on its pivotal supports to support the troughs in upwardly inclined positions.

The troughs in this form are shown as constructed generally of the character described above and are also capable of lateral swinging movement with respect to each other about the pivot 63. These troughs may be connected together intermediate their lengths by arms 70 which are pivoted together and pivotally connected with the respective troughs at 71, whereby the raising and lowering movements of the troughs will be uniform and at the same time the troughs may be held locked in their proper spaced relation, according to the comfort of the patient.

In this form, foot supports are shown at 72, each of which is mounted on a rod 73 extending transversely of an end of the trough. The rod 73 is supported by means of rods 74 extending longitudinally of the trough and telescoped with the rolled edges thereof for slidably mounting the foot support 72 on the outer end of the trough.

While the invention has been described for use as a leg and foot rest, it may be used not only for this purpose but also as an arm or hand rest by sliding the assembly along the bed rail to the shoulder sector. Furthermore, the device is useful also for resting under normal conditions where elevation of the leg and foot is desired. Moreover, it was practical to use in the treatment of varicose veins, high blood pressure, and other conditions where rest is desired.

While the invention has been illustrated and described in certain embodiments, it is recognized that these are illustrative of the invention and that variations and changes may be made therein, without departing from the invention, except insofar as specified in the claims.

I claim:

1. A limb rest comprising a supporting frame structure including aligned portions adapted to extend transversely of a bed, a plurality of elongated leg supports extending transversely of said portions, a bracket pivotally connected to each of said supports, means rotatably journaling each of said brackets independently on the respective portions for vertical swinging movement relative thereto to different angular positions with respect to the bed, and a yoke extending transversely over the leg supports and having opposite ends thereof connected with the journaling means in position for manual vertical movement to lift the leg supports to elevated positions, said yoke being positioned so as to be operated by an occupant lying in said bed beneath said yoke.

2. A limb rest comprising a frame structure including axially aligned spaced portions and adapted to extend transversely across a patient supporting device, means for securing said frame

structure in rigid relation to said device, a plurality of elongated leg supports extending transversely of said portions, a bracket pivotally connected to each of said supports, means rotatably journaling said brackets on the spaced portions for vertical swinging movement thereof relative to the patient supporting device, and a rod carried by the journaling means extending over the leg supports, said rod extending transversely over and substantially parallel to said supporting device in position to be grasped by a patient lying on said supporting device and beneath said rod and connected with the journaling means for tilting the leg supports relative to the supporting device.

3. A limb rest comprising a frame structure including axially aligned portions and adapted to extend transversely across a patient supporting device, means for securing said frame structure in rigid relation to said device, a plurality of elongated leg supports extending transversely of said portions, journal sleeve means mounted on said axially aligned portions and connected with the leg supports, a yoke extending transversely over the leg supports and having opposite ends thereof fixed to said journal sleeve means for turning said sleeve means relative to the supporting portions for moving the leg supports to an elevated position with respect to the patient supporting device and pivot means for horizontal adjustment of the leg supports.

4. A limb rest comprising a supporting device including axially aligned sections adapted to extend transversely of a patient supporting device, means for securing said sections to said device, sleeves rotatably journaled on said sections, brackets affixed to said sleeves, elongated leg supporting members extending transversely of said sections and means for pivotally connecting the leg supporting members independently to the brackets, manually operable means secured at each end to one of the sleeves for swinging said supporting members to elevated positions relative to the supporting device, said means extending transversely across the supporting members and above and within convenient reach of a patient lying beneath said operable means, and means for locking said supporting members in fixed elevated positions.

5. A leg rest comprising a supporting frame including a journal rod, a journal sleeve telescoped over said journal rod, a bracket fixed to said sleeve and extending laterally therefrom, a leg support extending over the bracket and pivotally connected therewith for laterally swinging movement relative to the sleeve and for upward swinging movement therewith relative to the journal rod, and stopping means for limiting the vertical swinging movement of the leg support, said stopping means being positioned in longitudinal alignment with said journal rod and spaced apart therefrom intermediate the rod and the ends of said support to limit the downward movement of the leg support when mounted upon a bed.

6. A leg rest comprising a supporting frame adapted to be mounted on a patient supporting device, a leg support connected with the frame, a foot rest connected with one end of the leg support, and a yoke over said foot rest pivotally connected thereto for applying traction to said foot.

7. A leg rest comprising a supporting frame adapted to be mounted on a patient supporting device, a leg support connected with the frame

and adapted to receive a leg thereon, a foot rest connected with one end of the limb support, means connected with the foot rest for applying traction to the leg when supported thereon, said traction applying means including supporting means for the foot rest, a yoke over said foot rest, and pivoted linked means for securing the foot rest and the yoke in different adjusted positions.

10 8. A limb rest comprising a limb supporting device, a supporting frame, means mounting the limb supporting device on the frame for swinging movement about an axis extending transversely of said limb supporting device, said mounting means including a bracket extending lengthwise of the limb supporting device, and pivot means fastening said limb supporting device to the bracket about an upright axis.

20 9. A limb rest comprising a supporting frame having a transverse journal rod, a sleeve journaled on the rod for turning movement relative thereto and having a bracket extending transversely from the sleeve and affixed thereto, a limb supporting device supported on the bracket, and an upright pin pivotally connecting the bracket to the limb supporting device.

30 10. A limb rest comprising a supporting frame structure including aligned portions adapted to extend transversely of a bed, a sleeve rotatably mounted upon each of said aligned portions, a bracket rigidly mounted upon each of said sleeves, and an elongated leg support extending transversely of each of said portions and pivotally connected to each of said brackets.

35 11. A limb rest comprising a supporting frame structure including portions adapted to extend transversely of a bed, a sleeve rotatably mounted upon each of said aligned portions, a plate rigidly mounted upon each of said sleeves, an elongated leg support extending transversely of each of said portions and pivotally mounted on each of said plates, and a yoke rigidly mounted at each end to each of said sleeves, said yoke extending transversely over the leg supports and positioned for manual swinging movement to lift the leg supports to elevated positions, said yoke being positioned so as to be operated by an occupant lying in said bed beneath said yoke.

40 12. A limb rest comprising a supporting frame structure including aligned portions adapted to extend transversely of a bed, a sleeve rotatably mounted upon each of said aligned portions, a plate rigidly mounted upon each of said sleeves, an elongated leg support extending transversely of each of said portions and pivotally mounted on each of said plates, and manually operable means secured to each of the sleeves for turning said sleeves relative to the aligned portions for elevating and lowering the leg supports with respect to the bed, said manually operable means being positioned above said leg supporting devices to permit operation thereof by an occupant lying on said bed beneath said manually operable means.

45 13. A limb rest comprising a supporting frame structure including aligned portions adapted to extend transversely of a bed, a pair of elongated leg supports extending transversely of said portions, means rotatably journaling each of said leg supports on the aligned portions for both vertical and lateral swinging and horizontal sliding movement relative thereto to different angular positions with respect to the bed, and stopping means carried by the supporting frame structure for limiting the downward swinging movement of the

leg supports in respect to the bed, said stopping means extending transversely of the leg supports and intermediate the frame structure and the ends of said leg supports.

14. A limb rest comprising a supporting frame including a transverse journal rod and depending arms spaced apart from each other and from the journal rod, said depending arms being connected to the rod and located side by side at one end of said rod, a clamp secured to each of said arms for attaching said frame to a side of a patient supporting device with the journal rod projecting inwardly thereover, a journal sleeve mounted on the rod for turning movement relative thereto, a bracket rigidly affixed to the journal sleeve, and a leg supporting device pivotally mounted on said bracket.
